(57) **CLAIM**

The ornamental design for a unidirectional, high torque open end wrench head, as shown and described.

DESCRIPTION

FIG. 1 is a front elevational view of a unidirectional, high torque open end wrench head showing my new design;

FIG. 2 is a left side elevational view thereof;

FIG. 3 is a right side elevational view thereof;

FIG. 4 is a top plan view thereof; and,

FIG. 5 is a bottom plan view thereof.

The rear of the unidirectional, high torque open end wrench head forms no part of the claimed design.
